UNITED STATES PATENT OFFICE.

ROBERT W. SCOTT, OF LEEDS POINT, NEW JERSEY, ASSIGNOR, BY DIRECT AND MESNE ASSIGNMENTS, TO SCOTT & WILLIAMS, INCORPORATED, OF CAMDEN, NEW JERSEY, A CORPORATION OF NEW JERSEY.

KNITTED WEB AND MAKING SAME.

1,081,779.

Specification of Letters Patent. Patented Dec. 16, 1913.

Application filed April 28, 1910. Serial No. 558,224.

To all whom it may concern:

Be it known that I, ROBERT W. SCOTT, a citizen of the United States, residing in Leeds Point, Atlantic county, New Jersey, have invented certain Improvements in Knitted Webs and Making Same, of which the following is a specification.

The object of my invention is to produce a knitted web of fine texture with the same facility as is experienced in knitting ordinary webs of coarser texture, my improved web also presenting a novel disposition of the yarns which distinguishes it from and renders it more attractive than an ordinary knitted web and lends itself to the brushing or gigging of one face of the web if a fleeced surface is desired, or to the introduction of weft threads. The improved web is also more elastic than a web in which the sinker 20 wales cross one or more needle wales.

In the accompanying drawings—Figures 1, 2, 3 and 4 are exaggerated views of pieces of knitted web produced in accordance with my invention, and Fig. 5 is a diagram representing the disposition of the knitting instrumentalities in a circular machine for producing my improved web.

The invention relates to single or plain webs having all of the stitches drawn in the same direction as distinguished from ribbed webs which have some of the stitches drawn in one direction and others in the opposite direction, the characteristic and novel features of the invention being the crossing of the sinker wales between adjoining needle wales by reason of the fact that the courses of stitches are "staggered", successive stitches of the same yarn being produced in different courses of the web, thus on reference to Fig. 1, it will be noted that the yarn *m* which produces stitches in course 2 of the wales *x* produces stitches in course 4 of the wales *y*, the yarn *m'* which produces stitches in course 4 of the wales *x* producing 45 stitches in course 6 of the wales *y*, and so on, the yarn *n* which produces stitches in course 3 of the wales *y* producing stitches in course 5 of the wales *x*, the yarn *n'* which produces stitches in course 5 of the wales *y* producing 50 stitches in course 7 of the wales *x*, and so on. Successive stitches in the wales and courses are also of different size, and there is a zigzag disposition of the stitches

which imparts to the web somewhat the same appearance as that of the web forming the subject of my Letters Patent No. 928,221, dated July 13, 1909. The crossing of the sinker wales on the back of the web imparts a distinctive appearance to both faces of the web and causes the sinker wales to project to such an extent that they can be conveniently brushed to form a fleece if a fleeced back is desired.

If it is desired to produce a web having weft threads therein, such, for instance, as the elastic threads sometimes employed in the manufacture of surgical goods, such weft threads can be conveniently introduced before the transfer of loops from the points to the needles, as hereinafter set forth. The introduction of the weft threads can be effected by means of a guide traveling in a plane between the tops of the retracted cylinder needles and the outer ends of the retracted dial hooks, so that it will lay its thread behind the stitches carried by the needles and on top of the loops carried by the hooks.

The fabric shown in Fig. 2 is similar to that shown in Fig. 1, with the exception that the stitches are displaced only to the extent of one course, the stitches which appear in odd numbered courses in the wales *x*, appearing in even numbered courses in the wales *y*, and vice versa, all of the long 85 stitches and all of the short stitches being in straight parallel rows. The fabric shown in Fig. 3 differs from that shown in Fig. 1 in having the courses staggered in adjoining groups of wales instead of in adjoining 90 single wales and consequently having the crossed sinker wales only between adjoining groups of wales. The fabric shown in Fig. 4 illustrates the same idea in connection with a web knitted in the manner 95 shown in Fig. 2.

In producing the webs shown in Figs. 1 and 2, I use a machine having two sets of needles A, B, a needle of one set alternating with a needle of the other set in a needle cylinder, needle bed, or other needle carrier, as shown for instance in Fig. 5, it being understood that my invention is applicable to straight knitting machines or to circular knitting machines, and to machines using either spring beard needles or latch needles.

Each set of needles is combined with the usual devices whereby it may be operated so as to cause it to knit, and also coöperating with the needles A and B are two sets of 5 loop receiving and transferring pins or points *a* and *b*, which may be disposed at a right angle to the needles A, B, in the same manner as the dial needles of an ordinary rib knitting machine, the points *a* being, however, by preference, in line radially with the needles B and the points *b* being in line 10 radially with the needles A, and said points being actuated so as either to receive a loop of yarn, or to transfer said loop to the opposed needle. One yarn is applied first to a needle A and then to a point *a* throughout the series and the other yarn is applied first to a needle B and then to a point *b* throughout the series.

20 Supposing that both yarns have been applied to the needles and points in the manner described to form a setting-up course, the first operation in knitting the fabric shown in Fig. 1 is to transfer the loops from 25 the points *a* to the needles B and to knock over on said transferred loops the loops previously applied to said needles B. The next operation is to apply fresh yarn to the needles A and points *a* and to knit on said 30 needles A by knocking over on the freshly applied loops of yarn the loops already on said needles. The loops are then transferred from the points *b* to the needles A and the stitches on the latter are knocked over 35 on said loops, the final operation being to apply yarn to the needles B and points *b* and to knit on said needles B by knocking over on the fresh loops, the stitches already on the needles, these operations being repeated indefinitely.

In knitting the fabric shown in Fig. 2, one 40 yarn is first applied to the needles A and points *a*, and the other yarn is then applied to the needles B, and points *b*, to form a 45 setting-up course, after which the loops are transferred from the points *a* to the needles B and from the points *b* to the needles A, and the loops previously applied to said 50 needles A and B are then knocked over on the transferred loops, yarn being then applied as before, the stitches on the needles then knocked over on the freshly applied loops, the loops then transferred from the hooks to the needles, the stitches on the latter knocked over on the transferred loops, and so on. In producing the fabrics shown 55 in Figs. 3 and 4, the same methods of operation are resorted to in connection with needles and points disposed in alternating 60 pairs instead of singly.

One of the advantages of my invention is the provision which it affords for knitting fine gage web with the same facility as is now experienced in knitting coarse gage

65 web, owing to the fact that the yarn is fed to and the stitches are drawn by alternate needles or groups of needles. This permits 70 of the knitting of relatively fine gage fabrics from linen or other refractory yarn which does not lend itself well to being 75 knitted in the usual way on machines of fine gage. The stitches which are produced from a loop of yarn laid directly upon the needles differ in size from the stitches produced by the transferred loops, thus 80 providing for the alternation of large and small 85 stitches in the wales and courses of the web.

I prefer in order to facilitate production, to use a machine having a plurality of yarn feeds, so as to supply one yarn to the needles A and points *a* and another yarn to the needles B and points *b*, but my improved 90 fabric can be knitted with one and the same yarn, by first knitting a course of stitches upon the needles A with intervening loops 95 applied to the loop holders *a* and then retaining said needles and loop holders out of action, while knitting a course of stitches upon the needles B with intervening loops applied to the loop holders *b*, the transfer 100 of loops from the loop holders to the corresponding needles and the knocking-over of the stitches upon said loops being effected in either of the ways hereinbefore set forth. Although I prefer to use transfer points or 105 pins, transferring needles, such for instance as those shown in my Letters Patent No. 834,763, dated October 30, 1906, may be substituted therefor, if desired.

I claim:

1. A knitted web having successively produced stitches of a course located in different but parallel course planes in adjoining wales, the sinker wales crossing each other.

2. A knitted web having successively produced stitches of a course located in different parallel course planes in adjoining needle wales, the sinker wales crossing each course and successive stitches in the needle wales being composed of different yarns.

3. A plain knitted web having successively produced stitches of a course located in different parallel course planes in adjoining needle wales, the stitches of said course in one course plane differing in size 115 from the stitches in said course in the other course plane, and the sinker wales crossing through the stitches of the other.

4. The mode herein described of producing a knitted web, said mode consisting in 120 disposing the knitting yarn or yarns to form a course of stitches with intervening loops, and another course of stitches with intervening loops alternating respectively with the stitches and loops of the first 125 course and drawing the loops of one course through the stitches of the other.

5. The mode herein described of produc-

ing a knitted web, said mode consisting in drawing in succession stitches and loops of one yarn and with another yarn drawing in succession stitches and loops alternating with those first produced, and drawing the loops of one yarn through the stitches of the other yarn.

In testimony whereof, I have signed my name to this specification, in the presence of two subscribing witnesses.

ROBERT W. SCOTT.
